UNITED STATES PATENT OFFICE.

HUGO J. BACHMAN, OF DENVER, COLORADO.

POPPET VALVE.

Application filed March 3, 1922. Serial No. 540,682.

To all whom it may concern:

Be it known that I, HUGO J. BACHMAN, a citizen of the United States, residing at Denver, in the county of Denver and State 5 of Colorado, have invented certain new and useful Improvements in Poppet Valves, of which the following is a specification.

My invention relates to poppet valves and more particularly to improvements in 10 valves of the type used in internal combustion engines to control the flow of motive fluid to and from their explosion chambers, and it is the primary object of the invention to provide a poppet valve of very simple form which in comparison with valves 15 of the solid construction commonly used, has an increased flow capacity in ratio to its lift.

I attain this object by forming in the head 20 of a poppet valve of suitable proportions, one or more ports which when the valve is in its closed position, are closed by its engagement with an auxiliary seat. When in the operation of the engine with which the 25 valve is associated, the latter is lifted off its seat, the flow of motive fluid through its opening is augmented by that passing through the ports, with the result that the capacity of the valve for the passage of fluid 30 is correspondingly increased in proportion to the extent to which it is moved by the action of its operating mechanism.

An additional advantage resulting from 35 the above described construction, resides in that the reduced area of the effective surface of the head of the valve, owing to the presence of the ports, correspondingly lowers the resistance to the opening movement of the same.

40 An embodiment of my invention has been illustrated in the accompanying drawings in the various views of which like parts are similarly designated and in which

Figure 1 represents a section of a part of 45 an internal combustion engine showing two valves constructed in accordance with the present invention, in sectional elevation;

Figure 2 a plan view of the improved valve;

50 Figure 3, a section taken on the line 3—3, Figure 2; and

Figure 4, a bottom view of the valve, showing the stem thereof in transverse section.

55 Referring more specifically to the drawings, the reference numeral 2 designates the

part of an engine to which the valve is applied, including a bevelled valve seat 3, a sleeve bearing 4 for the valve-stem, in the line of the axis thereof, and a conical auxiliary valve seat 5 at the end of the bearing. The valve 6 consists of a tapering head 7 at the end of a stem 8 which is slidably fitted in the bearing 4.

The head has at its outer end, a bevelled 65 face 9 co-operating with the correspondingly formed valve seat 3 and its inner end surface is dished as at 10 to fit upon the auxiliary valve seat when the valve is in its closed position.

The valve head has a number of ports 12 70 extending between its inner and outer surfaces, which in the construction shown in the drawing, flare at their outer ends.

When the valve is in its closed position, 75 as shown at the right hand side of Figure 1 of the drawings, these ports are closed by the engagement of the dished inner end of the valve with the correspondingly formed seat at the end of the stem-bearing, 80 and when the valve is lifted off its seat, as shown at the other side of the same figure, the ports are simultaneously uncovered, and the fluid confined at a side of the valve may thus pass through its opening not only by 85 the annular passage between its circumferential surface and the bevelled seat 3, but also by the passages provided by the open ports 12.

It will thus be evident that the flow 90 capacity of the valve is greatly increased over that of valves of solid head-construction, in ratio to its lift, and that the openings between the opposite surfaces of the head at the same time decrease the resistance to its 95 opening movement.

A kerf 13 in the outer end of the valve permits of the application of a screw driver for its adjustment or removal.

What I claim and desire to secure by Letters Patent is:

1. In a valve construction of the character described, a machine element having two axially aligned valve-seats, and a valve provided with faces adapted to simultaneously engage with said seats when the valve is in its closed position, said valve having ports which terminate in one of the faces, and are covered by the engagement of said face with the respective seat.

2. In a valve construction of the character described, a machine element having a bev-

elled seat and a conical seat in axial alignment therewith, and a valve having two faces which fit upon said seats in its closed position and having ports which terminate in one of said faces and are covered by its engagement with the conical seat.

3. In a valve construction of the character described, a machine element having a valve seat, a bearing for a valve-stem, and 10 an auxiliary valve seat at the end of the bearing, and a valve having a stem in said bearing and a head on the stem having two faces adapted to engage with said seats when the valve is in its closed position, the 15 head having ports which terminate in one of said faces and are covered by its engagement with the auxiliary seat.

4. In a valve construction of the character described, a machine element having a

valve seat, a bearing for a valve-stem, and 20 a conical valve-seat at the end of the bearing, and a valve having a stem in said bearing and a head on the stem, provided with two faces adapted to engage simultaneously 25 with both seats when the valve is in its closed position, the head having ports terminating in the face engaged by the conical seat.

5. In a valve construction of the character 30 described, a machine element having two valve-seats, and a valve having two faces which fit upon said seats, and having transverse ports which terminate in one of the faces and are covered by engagement of 35 said face with the respective seat.

In testimony whereof I have affixed my signature.

HUGO J. BACHMAN.
